[57] CLAIM

An ornamental design for an integrated door and frame, as shown and described.

DESCRIPTION

FIG. 1 is a front elevation of the integrated door and frame of the present invention, the broken lines showing a door pull are for illustrative purposes only and form no part of the claim design.

FIG. 2 is a rear view of an integrated door and frame of FIG. 1;

FIG. 3 is a side elevation, both sides being identical, of an integrated door and frame of FIG. 1; and,

FIG. 4 is a section taken through 4—4 of FIG. 1, showing the tongue and groove construction of an integrated door and frame of FIG. 1.

FIG. 1

FIG. 4

FIG. 2

FIG. 3
